UNITED STATES PATENT OFFICE.

RUDOLPH VUILLEUMIER, OF NEW ROCHELLE, NEW YORK, ASSIGNEE TO PINTSCH
COMPRESSING COMPANY, OF NEW YORK, N. Y., A CORPORATION OF NEW JERSEY.

APPARATUS FOR GENERATING HIGH-PRESSURE OIL-GAS.

1,038,691.

Specification of Letters Patent. Patented Sept. 17, 1912.

Application filed April 1, 1909. Serial No. 437,261.

To all whom it may concern:

Be it known that I, RUDOLPH VUILLEUMIER, a citizen of the United States, residing at New Rochelle, in the county of Westchester and State of New York, have invented certain new and useful Improvements in Apparatus for Generating High-Pressure Oil-Gas, of which the following is a full, clear, and exact description, such as will enable others skilled in the art to which it appertains to make and use the same.

This invention broadly deals with systems for converting hydro-carbons into fixed gases, but more particularly it concerns an apparatus for producing gas of high illuminating power and under high pressure from low grade mineral oils. Since, however, certain advantages characteristic of this invention prominently appear when crude oil is decomposed in the presence of superheated steam under high pressure and is under the manipulation of steam otherwise subjected to a predetermined cycle of operations, it will be conducive to clearness to fully disclose this invention by way of such specific embodiment. The nature of this system is such that its full disclosure may be greatly facilitated by describing the various characteristic features of construction thereof, in conjunction with statements detailing the manner in which the oil will course through and undergo essential change in quality in the various parts of the apparatus.

In the drawings, like characters of reference denote corresponding parts throughout the several views, of which—

Figure 1 is a general diagrammatic representation of the various correlated major elements of my apparatus for decomposing crude oil into a fixed gas; Fig. 2 is a sectional diagrammatic representation showing various details of construction and arrangement not illustrated in Fig. 1.

As conducing to a better understanding of the nature of my simple system for efficiently converting crude petroleum or the like into gas of high illuminating power, it will be of advantage to briefly outline the same, preliminary to a more detailed discussion thereof. An inclosed reticulated framework or checker-work of fire-brick is first brought to a high temperature, *i. e.* not materially exceeding 1200° Fahrenheit, and this stored-up heat is then utilized under

certain peculiar conditions as a means for decomposing the crude oil into gas. This petroleum is injected in the form of a spray into one portion of this intensely heated checker-work, and at the same time superheated steam under high pressure is also admitted. The decomposition which takes place in the presence of an atmosphere of steam almost entirely prevents the deposit of carbon on the checker-work (what does collect is burned out during the next heating-up cycle). This steam, together with the fixed gas, as well as tarry matter and some lamp-black resulting from the decomposition of the oil, is then passed through a porous, highly heated mass of some suitable scrubbing material such as coke, so as to entirely retain such lamp-black as may escape from the generator along with the fixed gas. After this, the fixed gas, admixed with steam and some tarry matter, is forced through a preheating apparatus wherein it gives up much of its heat to incoming crude oil and then passes through the condenser into a reservoir; the pressure in the generator and parts leading to the reservoir being at about 14 to 15 atmospheres toward the end of the gas making cycle. When the gas mixed with steam, and also containing tarry matter, enters the condenser 37, the latter two ingredients condense; the steam to water, and the tarry matter to a more or less fluid tar which is used as a fuel in the preliminary heating of the generator. These products then enter the reservoir. In fact, under certain conditions, there may be enough of this tarry by-product to furnish all the fuel that may be necessary for the heating of the generator. It should also be stated that the incoming original oil which is supplied to the generator flows through pipes in intimate contact with the discharge pipes of the resulting gas, and, in consequence, the incoming original oil thus absorbs heat from the outgoing fixed gas, and this saving of heat works a further economy in the system. The forcing of the original oil into the generator is also accomplished without involved mechanical appliances, such as pumps, by means of steam. That is to say, I employ two tanks, the one containing crude oil and the other containing some gas under pressure more or less mixed with and displaced by steam. These tanks are connected by a suitable pipe in which is in-

terposed a condenser, the function of which is to prevent steam from passing over from the pressure-tank to the oil-feed tank and condensing in the latter as water. After the generator has run a short time, say eight minutes, the flow of oil is stopped and for a while steam is blown through to force the residual gases into the reservoir, after which the admission of further steam is stopped, and the residual steam still confined in the generator is permitted to escape; whereupon combustible material is once more injected into the generator and therein burned so as to again store up in the generator sufficient heat to accomplish the decomposition of the oil into gas during the following gas making cycle.

The boiler.—This is indicated by A on the drawings and is utilized as a source of steam, the particular type of boiler not being an essential part of this invention so long as it efficiently produces steam in sufficient quantities and at a suitable pressure, which in this case will be about 17 atmospheres. In this embodiment, the steam from this boiler is employed, first, for the purpose of injecting fluid and air into the generator so as to bring the same to a high temperature as a result of combustion; second, for forcing the crude petroleum through various parts of the apparatus and into the generator where it will be volatilized and decomposed into gas; third, to provide a catalytically acting atmosphere within the generator to promote the desired decomposition of the crude oil; fourth, to serve as a means instrumental in furnishing the pressure needed to force the resultant oil-gas through the various parts of the apparatus into the reservoir; and fifth, as a means for cleaning out the reservoir of all residual gas remaining at the end of the gas making cycle and of sweeping this residual gas into the reservoir, thereby preparing the generator for the reception of the combustible matter used to raise up the temperature of such generator preparatory to starting the cycle of gas making. It will be convenient, in following out this description, to consider these operations in the above-mentioned sequence.

The gas-generator.—This is indicated on the drawings by the character B and acts alternatively to store up heat and then to yield up this stored heat in decomposing oil into a fixed gas. It preferably assumes the shape of an upstanding cylinder formed exteriorly of a moderately heavy steel shell 1. This shell is interiorly lined with some suitable non-conducting refractory material 2, such as fire-brick and asbestos, and is filled more or less as illustrated in the drawings, with a reticulated mass or framework such as the checker-work 3 of fire-brick. This oil-decomposing checker-work extends

from a point near the base of the generator to a point somewhat above the middle of the generator. The upper part of the generator is also provided with a secondary or steam-superheating checker-work 4 which is preferably spaced somewhat above the first-mentioned oil-decomposing checker-work 3 so as to provide what may be regarded as an oil-spraying chamber 5, this chamber being intermediate the upper superheating and lower decomposing checker-works. A hearth 6, preferably of refractory material, underlies the oil-decomposing checker-work 3 so as to provide a combustion chamber or fire place 7. The part of the generator above the steam-superheating checker-work provides a stack 8 controlled by a large stack-valve 9, which permits of the escape of the products of combustion resulting from the heating up of the generator preparatory to the subsequent admission of oil and resultant generation of gas; this stack-valve 9 may be tightly closed so that during the gas making cycle the vaporous contents of the generator may be brought to and maintained at a pressure upward of 14 atmospheres. A valve 10 is also provided for the purpose of admitting the fuel such as tarry matter intersprayed with air which, by burning in the generator, raises the temperature thereof. While but one generator has been shown, this disclosure will make it obvious that two or more may be connected together in series or parallel, although the shown arrangement is regarded as preferable because of its essential simplicity, which constitutes an all-important factor in the commercial generation of high pressure gas.

Prominent characteristics of generator.— It may be here pointed out that gas under high pressure has heretofore been made by strongly heating oil in heavy iron retorts of small diameter which were externally subjected to a high heat. This, however, involved some very considerable difficulties, inasmuch as under the requisite high heat the iron retorts rapidly deteriorated; and it was also found that not only the retorts, but other portions of the apparatus, would quickly fill with lamp-black and carbon, so that the brief period during which the gas could be made was necessarily followed by a long and laborious period of cleaning out and replacing the retorts and other portions of the apparatus. Again, according to such prior practice, the gas was not generated under the full high pressure of from 14 to 15 atmospheres which is used in car and buoy lighting or otherwise where storage, distribution or use of high-pressure oil-gas is of primary importance. Consequently, the gas, as heretofore made had to be compressed by a steam-driven compressing apparatus up to a pressure of about 14 atmos.

phers for distribution to the cars at pressures up to 12 atmospheres. This part of my system has, then, the three-fold object in direct contemplation: first, to employ an impervious metal shell which will be protected from the injurious direct action of the burning matter by means of an internal lining of fire-proof material, thereby rendering it feasible to withstand the high pressure of the gas by means of a much lighter and less expensive shell than has heretofore been possible. Moreover, by following my construction, generators of very much increased capacities over those heretofore utilized⁶ are rendered commercially available with a concomitantly pronounced effectiveness. So also, by this method the wear and tear is entirely confined to the lining, which is not only made of comparatively inexpensive material, but which, being of a refractory nature, is far more resistant to heat than iron or steel. Furthermore, this lining, being a poor conductor of heat, greatly reduces the waste of heat, and hence the operating expenses.

Second: By carrying on the combustion in the same chamber and interstices in which the oil was decomposed, with the consequential deposition of more or less lamp-black on the walls thereof, such deposited carbon will be burnt out during the combustion, thereby dispensing with the necessity of frequently cleaning out the generator, and at the same time the surfaces with which the oily-vapors will subsequently contact are the most intensely heated.

Third: To eliminate the losses and delays incidental to the external heating of the thick walled retorts heretofore used by reason of the fact that in such old devices it was necessary for the heat to be conducted through such thick walls before being available in the interior.

Restoring temperature of generator preparatory to gas-making.—Assuming that this cycle has immediately followed a gas making cycle, the fire-brick checker-work in the generator will still be at a comparatively high temperature—sufficiently so to ignite the injected fuel, though not capable of very much longer yielding up the heat requisite to the proper decomposition of the oil into a fixed gas. The generator will now be filled with oily-vapors, superheated steam and fixed illuminating gases. To first get rid of this, the admission of oil is discontinued and steam is permitted to flow into the generator for a short time, say four minutes, thereby displacing and saving these valuable products by forcing them into the storage reservoir, as will subsequently be more fully described. This still leaves the generator full of steam under pressure of from 14 to 15 atmospheres, and this steam is then allowed to escape through the stack

of the generator by opening valve 9 and closing all other valves save valve 10, which will shortly be opened. The function of this latter valve 10 is to inject fuel and the air for its combustion into the generator, 70 therein to burn. This injected fuel may consist of any suitable material, and may contain tar obtained as a by-product from the reservoir or elsewhere. This fuel may conveniently be injected into the generator 75 by means of steam obtained from the boiler A, and sufficient air for combustion may at the same time be drawn into the combustion chamber through valve 10 by natural draft or by aspiration, or otherwise. The products of combustion pass upwardly, first through the lower gas making checker-work, and then through the upper steam-superheating checker-work, and raise the same to a very high temperature, especially 80 85 the oil-decomposing checker-work the lower portion of which will be very intensely heated and will serve as a final superheating surface for the fixed gases resulting from the decomposition of the oil. The upper portions 85 of the lower or oil-decomposing checker-work 3 will be highly heated, though to a less degree than the lower portion, and will be thus well adapted to serve to vaporize the hot oil incoming from the pre-heating apparatus. The upper or secondary checker-work 4 serves mainly as a final absorber and regenerator of the heat of the products of combustion, so that the major portion of the available heat energy resulting from the combustion of the fuel will be 95 effectively absorbed by the generator prior to the final discharge of the products of combustion through the stack 8 and the draft valve 9. Since the steam which is 100 introduced during the period of gas-making enters the generator at its top, such steam first encounters the uppermost or secondary checker-work 4 which forthwith gives up its stored heat to such steam, thereby superheating the latter before it commingles with the sprayed-in oil.

Apparatus for introducing crude oil by steam.—By the means for handling crude oil about to be described, I am enabled to entirely do away with complicated moving mechanisms such as pumps and the like, and at the same time secure a safer, better and more perfect control and handling of the crude oil. In lieu of such complicated moving apparatus, I have devised the oil-feeding device comprising tanks C and D shown in the drawings. C is a pressure tank into which steam is admitted for the purpose of providing the pressure requisite for the 115 forcing of the crude oil through the apparatus into the generator. The steam for this purpose is obtained from the boiler by means of pipe 13 (see Fig. 1), which is controlled by the valve 14. The companion 120 125 130

tank D contains the crude oil, which may be admitted to the same by means of valve 17 in the bottom; the amount of oil in such oil feed tank being ascertainable by a gage 19 of special design, and providing a sliding scale 18 which may have its graduations expressed in gallons or other units of measurement, as may be preferred. Both of these tanks are adapted to withstand a high pressure and are connected together at the top by means of the loop-pipe 20. The leg of this loop-pipe which extends upwardly from the pressure tank C is provided with a condenser E which may assume any desired form, as, for instance, that shown on the drawing, in which the uprising leg of the connecting loop is surrounded by a jacket-pipe 21 having an inlet at 22 and an outlet at 23 for the flow of cooling water, whereby the steam which may succeed in entering the pipe leg will be condensed forthwith, thus effectually preventing the steam from passing over through the loop-pipe 20 into the oil-feed tank.

Operation of steam for feeding oil.—The oil tank D is first nearly filled with oil through the valve 17 by means of a steam pump or otherwise until the gage glass indicates it to have nearly filled such tank. The adjacent pressure tank C is filled with fixed gas under pressure by means of pipe J communicating with the reservoir G, and as soon as a sufficient amount of this fixed gas has been introduced the connection with the reservoir G is cut off so that a back-flow may not take place during the subsequent introduction of steam under a greater pressure. The pressure tank, therefore, contains an initial charge of compressed fixed gas. By virtue of the connecting pipe 20 the pressure will be equal in these two tanks, and the oil in the tank D will therefore be under a medium pressure, which, however, will be insufficient to force the oil into the generator against this working pressure. This moderately compressed fixed gas of course fills both of the tanks as well as the intervening connection. That is to say, the full working pressure in the generator will be about 15 atmospheres, and in order that the oil may be successfully injected, it must exceed the generator pressure by about one to two atmospheres. This, however, is readily accomplished by admitting high pressure steam into the lower part of the pressure tank C through the valve 14, which steam will, of course, force some of the gas over into the oil-feed tank D by partly displacing its equivalent volume in pressure tank C and also partly by heating, and accordingly, expanding the fixed gas. In other words, the fixed non-condensable gas operates as a cushion so to speak in transmitting the pressure of the steam 65 through the connecting pipe into the oil

tank without its being necessary for such steam to actually pass through said pipe into the oil. As a result, after a few seconds after the steam has been turned on, both the oil feed tank and the pressure tank 70 will have reached a pressure very nearly corresponding to that of the steam boiler, which pressure will be maintained during the entire period of gas-making and will suffice to force the oil into the generator 75 against the working pressure thereof. The steam which has been admitted into the pressure tank C tends to diffuse to a certain extent through the fixed gas but the small quantity of this steam that tends to 80 rise in this way into the connecting pipe 20 is unable to pass over into the companion oil-feed tank D, since the cooling jacket or condenser E is interposed and will forthwith condense any steam which may rise in 85 the leg 21, and the resulting water will be returned by gravity to the bottom of the pressure tank, from which it may be drawn through pipe 15 from time to time.

It will be perceived from the above that 90 through the instrumentality of the fixed gas the steam which itself, is incapable of passing by the condenser is nevertheless enabled to produce the desired pressure on the oil in the other vessel.

Apparatus for preheating oil.—This apparatus F is interposed in the pipe 24 which conveys the oil to the generator and enhances the economy of operation of the entire system. The apparatus consists of one 100 or more coils 25 of piping through which pass the highly heated products resulting from gas making. These coils are, however, incased within jackets 26, each of which is provided at one end with a suitable expansion joint. The crude oil entering through pipe 24, passes into the jackets 26 so as to circumscribe the internal coils 25, and accordingly, extract a large part of the available heat from the same. It should be 105 stated that the incoming oil which passes in series through these jackets, does so in opposite directions to the flow of the outgoing gas, thereby increasing the effectiveness of the heat transference from the gas 110 to the oil. Of course, these jackets may be varied in number and size and may assume divers forms, though that shown is simple and efficient and has the advantage of being very accessible for cleaning out the inner pipe through which the gas outcomes. The oil, in emerging from the pre-heater, flows through pipe 27 into the generator at a point 28 and enters the oil spraying chamber 5 in the form of a fine spray, this being 115 done by means of oil spraying nozzles, which are of well known designs such as that shown. An oil inlet valve 29 is interposed in the pipe 27 so as to control the admission of oil during the period of gas mak- 120 125 130

ing, and so as to enable the flow of oil to be stopped entirely during the "sweeping-out", "blowing-off" and "heating-up" cycles.

5 *Gas making from pre-heated oil in the pre-heated generator.*—In the foregoing, the method of bringing the generator and its contained refractory checker-work to a high temperature has been set forth. This having been done and sufficient heat having been stored up in such generator, the cycle of decomposing the oil into fixed gas (which ordinarily lasts for about eight minutes) may now take place. Stack-valve 9 and 10 fuel-injecting valve 10 will be closed, and now valve 14, admitting steam to the pressure tank to feed the crude oil, will be opened, as will also valve 30, which admits steam into the stack of the generator. The 20 effect of this is to immediately bring the pressure of the oil in the feed-tank D to very nearly the normal boiler pressure, and steam will also begin to flow into the intensely heated generator to gradually fill 25 the same with steam and displace any residual air, so that the pressure will slowly rise in such generator. The incoming steam first infiltrates through the secondary, or superheating checker-work 4, and as this is 30 now at a very high temperature (though not so hot as the lower checker-work 3), the steam will be immediately superheated and further along will acquire still more heat. When the pressure in the generator 35 has risen to about 8 atmospheres (the generator being full of superheated steam), the oil valve 29 will be opened and the oil will be forced by the pressure of the oil feed tank D through the pipe 24 into and through 40 the preheater F, thence through the pipe 27 in its preheated form into the spraying chamber of the generator in the form of a fine spray in consequence of the oil spraying nozzles, which are shown at or about the 45 point 28. As soon as the oil admission valve 29 is opened, the main-valve 31, which is interposed in the outlet pipe 25 and which leads into the storing tank or receiver G, is opened. Adjacent the main valve 31 50 there is also a check-valve 32 which will open just as soon as the pressure in the generator reaches that of the storeholder. The admission of the incoming steam to the generator is controlled by some suitable means, 55 as, for example, an orifice of fixed predetermined diameter, so as to keep the flow of steam a fixed quantity. The flow of the oil may also be known by an observation of the sliding scale 18 attached to the feed 60 glass 19 on the oil feed tank, and the flow of such oil may thus be readily regulated according to the circumstances.

The oil enters the generator, being injected in the form of a fine spray into the 65 spraying chamber 5, wherein it intimately

commingles with the superheated steam which already fills the generator. The mixture of oil vapor and superheated steam flows downwardly from the oil spraying chamber 5 and infiltrates through the still 70 more intensely heated primary checker-work 3, whereupon the oil spray is first converted into a vapor and then becomes intensely superheated and ultimately entirely brought into the condition of a fixed gas. 75 The steam filling the generator and intermingling with the vaporized oil does not appear to react with the carbonaceous material freed from such oil by decomposing it into a low candle-power gas as might be 80 surmised, but under proper working conditions, its action appears to be more of a catalytic nature and appears to exert some sort of a protective influence upon the oil vapor, enabling the latter to transform 85 into a gas of very good illuminating power without producing the abundant deposition of carbon in the form of lamp-black or otherwise which invariably occurred according to prior methods. It is to be understood, however, that some carbonaceous material, either in the form of lamp-black or otherwise, will be left behind on the checker-work and burnt out during the next heating-up, although observations tend to indicate that 90 all the steam originally admitted will subsequently reappear as condensed water, from which it is believed that the steam acts as a catalyst. It will be noted that this system works a great economy over externally-heated retorts, since the most intensely heated surfaces of the confined checker-work are those which directly contact with the oil vapors to be decomposed into a 95 fixed gas. It is also to be observed that, inasmuch as the pressures throughout the system are positively controlled by and are directly dependent upon the boiler-pressure, the system is safeguarded against accidental and neglectful operations, which is a matter 100 105 of paramount consequence. Furthermore, by making the inflow of oil into the generator directly dependent upon the boiler-pressure, the system becomes quite independent of mechanically-acting high pressure pumps with a concomitant improvement in the uniformity and reliability of the oil flow in addition to a marked simplification from the standpoint of the operator.

110 *The high temperature scrubber.*—This is indicated by H and consists of a cylindrical shell 34 of steel or other suitable material having cleaning-out caps 36 and filled with a porous refractory scrubbing material 35 suitable for high temperature, such as coke 115 and the like. This scrubber is maintained at a high temperature by the out-going gas. It is connected with the generator by means of a pipe such as that indicated by 33, so that the oil gas plus the tarry matter and the 120 125 130

superheated steam will enter one end of the scrubber and infiltrate through the highly heated porous contents thereof and ultimately pass out through pipe 25 connected with the 5 other end of such scrubber. The function of this scrubber, which is at a high temperature, is to absorb or otherwise eliminate the lamp-black and carbon from the vaporized products of the generator, thereby preventing 10 a precipitation of carbon and lamp-black in the succeeding portions of the apparatus, thus keeping all connecting pipes, cooling jackets and the like clean, and therefore in efficient condition for good service. Furthermore, 15 this scrubber also tends to prevent the lamp-black from being carried over and mixed with the by-product of the gas after condensation, a feature of which is of considerable importance in connection with the use subsequently made of this by-product. The products of the composition, 20 after leaving the scrubber, pass through the coils 25 of the oil heating jackets F wherein much of the heat of such decomposition products is absorbed by the crude oil flowing 25 in a contrary direction toward the generator. After leaving such coils 25, the gas, together with some tarry matter and superheated steam, will pass through the 30 denser 37, wherein the tarry matter and steam will be condensed, and then through the check-valve 32 and the main valve 31 into the store tank or reservoir G.

Sweeping-out generator.—This operation follows the period of gas making and precedes the period of heating up the generator for a second gas making period. After the above-mentioned gas making period has gone on for in the neighborhood of eight 40 minutes and a pressure of from 14 to 15 atmospheres has been attained in the making of the gas, this operation will be brought to a close by turning off the oil-valve 29 and also the valve 14 of the pressure tank C. The incoming steam valve 30 in the stack of the generator will not, however, be turned off until steam has been permitted to flow into the generator for about four minutes. This steam serves to displace the oil-gas 50 which may fill the generator and pushes such oil-gas from the generator into the scrubber, through the heating jackets and ultimately into the storeholder or reservoir G. After this has been done and the generator has been substantially freed from any 55 oil-gas, all valves are closed and the steam remaining in the generator will be exhausted through the stack-valve 9, or it may be exhausted through a suitable feed-water heater to preheat the water for the boiler as a matter 60 of economy if desired. This exhaustion of the steam from the generator will, of course, reduce the pressure in such generator to about atmospheric pressure and the generator will be ready for another heating 65

up, which will last for about ten minutes, whereupon the cycle above described will be repeated.

From the foregoing disclosure, it will be perceived that I have devised a very efficient and serviceable system for converting crude petroleum or any of its ingredients or distillates or equivalents (or any other hydrocarbon suitable for gas making according to this process), into a fixed gas of good illuminating power and under a pressure of about 14 or 15 atmospheres; or higher if desired. 70

Attention may also be directed to the fact that by heating up the generator in a direction opposite to that in which the hydrocarbonaceous material travels through the same, several noteworthy advantages are obtained. Thus: the necessity of having in connection with the generating chamber a separate superheating is obviated; an economy in heating-up the generator is secured; and the oil is introduced into a part of the generator which is at lower temperature than the discharge region, thereby somewhat reducing 80 the carbonization while at the same time more efficiently utilizing the lower temperatures of the generator. 85

In referring to the steam as being under "high pressure" in the above description and throughout the following claims, a pressure is denoted which is abnormal with reference to prior practices which may otherwise superficially appear similar to certain aspects of the process described in connection with the apparatus forming the subject matter of this invention. That is to say, in such instances, the use of a pressure more or less closely approximating fourteen atmospheres is regarded as a distinguishing 95 feature in view of the radical changes in capacities and reactions of the processes. 100

As many changes could be made in the above construction and many apparently widely different embodiments of this invention could be made without departing from the scope thereof, it is intended that all matter contained in the above description or shown in the accompanying drawings shall be interpreted as illustrative and not in a 110 limiting sense. 115

It is also to be understood that the language used in the following claims is intended to cover all of the generic and specific features of the invention herein described, and all statements of the scope of the invention which, as a matter of language, might be said to fall therebetween. 120

Having described my invention, what I claim as new and desire to secure by Letters Patent is: 125

1. An apparatus adapted to produce high candle-power gas under high pressure, combining a generator, means for internally heating the same, a pre-heater, means for 130

introducing oil through said pre-heater into said internally heated generator, means for removing the resultant fixed gases through said pre-heater, and means adapted to maintain throughout said apparatus a pressure of approximately fourteen atmospheres.

2. An apparatus adapted to produce high candle power gas under high pressure combining, a generator adapted to be brought to a high temperature, means for internally heating the generator, a preheater, means for introducing through said preheater finely divided oil under steam pressure into said generator, means for introducing steam to displace through said preheater the products of decomposition of said oil resulting from its exposure to the heat in said generator and means adapted to maintain throughout said apparatus a pressure of approximately fourteen atmospheres.

3. An apparatus adapted to produce high candle power gas under high pressure combining, a generator adapted to be brought to a high temperature, means for internally heating the generator, means for filling said heated generator with steam, means for introducing finely divided oil into said steam-filled generator, a scrubber, means for removing through said scrubber the products of decomposition of said oil and a source of steam adapted to maintain throughout said apparatus a pressure of approximately fourteen atmospheres.

4. An apparatus adapted to produce high candle power gas under high pressure combining, a generator adapted to be brought to a high temperature, means for internally heating the generator, means for preliminarily filling said generator with steam, means for simultaneously introducing steam and oil, means for scrubbing the resultant products of decomposition of said oil and a source of steam adapted to maintain throughout said apparatus a pressure of approximately fourteen atmospheres.

5. An apparatus adapted to produce high candle power gas under high pressure combining, a generator containing reticulated refractory material, means for maintaining a combustion within said generator to preheat the contents thereof, means for discharging the products of combustion, means for introducing steam, means for introducing oil, a store-holder adapted to receive the products of decomposition of said oil and a source of steam adapted to maintain throughout said apparatus a pressure of approximately fourteen atmospheres.

6. An apparatus adapted to produce high candle power gas under high pressure, combining a generator containing reticulated refractory material, means for maintaining a combustion within said generator to preheat said material, means for introducing finely divided oil into said preheated generator,

means for introducing steam under pressure to sweep the products of decomposition under pressure into a containing vessel and a source of steam adapted to maintain throughout said apparatus a pressure of approximately fourteen atmospheres.

7. An apparatus adapted to produce high candle power gas under high pressure combining, a generator containing reticulated refractory material, means for maintaining a combustion within said generator to preheat said material, means for simultaneously introducing under pressure finely divided oil and steam into said generator, a store-holder, a scrubber intervening between said generator and said store-holder, means for sweeping the products of decomposition from said generator through said scrubber and into said store-holder and a source of steam adapted to maintain throughout said apparatus a pressure of approximately fourteen atmospheres.

8. An apparatus of the nature disclosed comprising, in combination, a generator constructed to be preheated, a vessel connected with said generator and adapted to contain oil, a compartment connected with said vessel, means for filling said vessel compartment and connections therebetween with gas and means for introducing steam into said compartment to compress said gas to force said oil under pressure into said generator.

9. An apparatus of the nature disclosed comprising, in combination, a generator 100 constructed to be preheated, a store-holder for containing fixed gases produced by said generator, a vessel containing oil connected with said generator, a conduit connecting said vessel with said store-holder for admitting 105 an initial charge of fixed gas into said vessel, a tank connected with piping to said vessel, a condenser in operative arrangement with said piping, and means for introducing steam into said tank to communicate pressure to said oil through the initial charge of fixed gas to force the oil from said vessel into said generator.

10. An apparatus of the nature disclosed, comprising in combination, a generator 115 containing reticulated refractory material, means adapted to internally preheat said generator to a temperature not materially exceeding 1200° Fahrenheit, means for filling said generator with steam at a pressure 120 of approximately fourteen atmospheres, means for introducing finely divided oil into said generator while at said temperature and under said pressure, a scrubber connected with said generator, a gas tank 125 connected with said scrubber, an oil pre-heater intervening between said scrubber and said gas tank constructed to be maintained at a high temperature by the gases forced from said scrubber into said tank, a 130

- vessel containing oil, a conduit leading from a lower point of said vessel through said preheater to said means for introducing oil; a steam tank, a connection between the upper ends of said oil vessel and said steam tank, means for introducing a fixed gas to said oil vessel and said steam tank, means for introducing high pressure steam into said steam tank whereby said gas may act as a means instrumental in transmitting the pressure of said steam to said oil to enable the latter to be forced into said generator.
11. An apparatus of the nature disclosed, comprising in combination, a generator adapted to be brought to a high temperature, means for internally heating the generator, a preheater, and means for introducing through said preheater finely divided

oil under steam pressure into said generator, said oil being substantially out of contact with said steam.

12. An apparatus of the nature disclosed, comprising in combination, a generator adapted to be brought to a high temperature, means for internally heating the generator, a preheater, and means for introducing through said preheater finely divided oil under fluid pressure into said generator, said fluid being substantially prevented from entering said generator.

In testimony whereof I affix my signature, in the presence of two witnesses.

RUDOLPH VUILLEUMIER.

Witnesses:

ELMER E. ALLBEE,
JOHN T. CLARK.
